UNITED STATES PATENT OFFICE.

DAVID GEORGE AND JOHN D. GEORGE, OF DETROIT, MICHIGAN.

DESIGN FOR A SEWER-TILE.

SPECIFICATION forming part of Design No. 31,891, dated November 28, 1899.

Application filed October 18, 1899. Serial No. 734,033. Term of patent 14 years.

To all whom it may concern:

Be it known that we, DAVID GEORGE and JOHN D. GEORGE, citizens of the United States, residing at Detroit, in the county of Wayne and State of Michigan, have invented and produced a new and original Design for a Sewer-Tile, of which the following is a specification, reference being had to the accompanying drawings, forming part thereof.

Figure 1 is a side elevation of a sewer-tile, showing our new design; and Fig. 2, a vertical section of the same, taken on the line 2 2 of Fig. 1.

As shown in the drawings, the leading or material feature of our design consists of the curved sides A' A' of the body, the inwardly-projecting circumferential ledge B, and the flanged branch C. The upper portion of the body A for about one-half its length is cylindrical and the lower portion of the body is oppositely curved inward and downward,

forming a reduced lower end. The upper end of the body is provided with an upwardly and outwardly projecting shouldered flange D, and near said upper end is a branch C, having its axis at right angles to the axis of the body A and also having a shouldered flange C'. In the body A, at about one-third the distance from the lower end, is an inwardly-projecting circumferential ledge B.

Having described our invention, what we claim, and desire to secure by Letters Patent, is—

The design for a sewer-tile, as herein shown and described.

In testimony whereof we affix our signatures in presence of two witnesses.

DAVID GEORGE.
JOHN D. GEORGE.

Witnesses:

FRANKLIN L. LORD,
WILLIAM T. STARK.
